UNITED STATES PATENT OFFICE.

DAN NEWTON, OF JAMESTOWN, NEW YORK, ASSIGNOR OF ONE-HALF TO CHARLES E. BRINK, OF JAMESTOWN, NEW YORK.

WINDOW-PLATFORM.

1,351,434.

Specification of Letters Patent. Patented Aug. 31, 1920.

Application filed March 29, 1920. Serial No. 369,794.

To all whom it may concern:

Be it known that I, DAN NEWTON, a citizen of the United States, residing at the city of Jamestown, in the county of Chautauqua and State of New York, have invented certain new and useful Improvements in Window-Platforms, of which the following, taken in connection with the accompanying drawings, is a specification.

10 The invention relates to window platforms or scaffolding for the use of window cleaners, glaziers and similar workmen; and the object of the improvement is to provide a durable and strong knock-down window platform construction which is supported on the window casing at each side so that it can support heavy weights, holding rigidly in place when set up, the assembling being easy of accomplishment and the parts adjustable to different sized windows; and the invention consists in the novel features and combinations hereinafter set forth and claimed.

15 In the drawings, Figure 1 is a perspective view of the preferred form of the window platform, showing the construction and arrangement of the same. Fig. 2 is a plan view of the window sill with the inner ends of the holding brackets supported by the cross rod in position against the window casing, the wall and casing being shown in section and the outer portion of the brackets being broken away. Fig. 3 is a perspective view of one of the supporting brackets in position upon the window sill, the wall being shown in section. Fig. 4 is a side elevation of one of the preferred forms of clamps for holding the platform on the supporting brackets and giving rigidity to the entire structure; and Fig. 5 is a perspective view of the adjustable locking rod for holding the inner ends of the brackets against the inner side of the window casing; and Fig. 6 is a perspective view of the tubular covering for the rod to prevent marring the finish of the window casing.

Like characters of reference refer to corresponding parts in the several views.

50 The numeral 10 designates one of the supporting brackets, and the numeral 11, the other.

Each of the brackets 10 and 11 consists preferably of the three bars 12, 13 and the cross bar 14. The bar 12 has the spaced

holes 15 therethrough in its inner portion and the upwardly projecting outer end 16. The bar 13 is bolted to the outer end of the bar 12 at 17, and the cross bar or brace 14 is bolted at 18 to the bar 13 and at 19 to 60 the bar 12.

A cross rod 20 is provided which slidably fits through the holes 15 of each of the brackets 10 and 11, and extends out each side of said brackets to bear against the 65 inner side of the window casing 21. For finely finished casings, a tubular covering 28 is provided for the rod 20 to prevent marring the finish.

The platform 23 preferably has the rail- 70 ing 24 thereon and when the brackets 10 and 11 are placed in position upon the window sill 22 at each side of the window and the rod 20 is inserted in position to hold the same with the lower ends 25 of 75 the bars 13 resting against the wall of the building, the platform 23 can be placed upon said brackets 10 and 11 and hold firmly in position by means of the screw clamps 26 and 27, which clamps bear on 80 the under side of the bars 12 and the upper side of the platform 23.

It is apparent that this construction gives a knock-down and easily adjustable window platform which is held rigidly in position 85 by means of the cross bar 20, and which holds the workman in position without danger of falling, the support of the rod 20 being sufficient to uphold an exceedingly heavy weight. When knocked down, the 90 window platform is easily portable from one window to another, or from one building to another, or for shipment, and the construction is such that while durable, it is exceedingly easy of manufacture and as- 95 semblage.

I claim as new:

A window platform including a pair of independent and freely adjustable bars each formed to abut the respective sides of the 100 window frame and having a series of openings in their inner end portions and having their outer ends enlarged and extending upwardly to form stop shoulders, braces for the bars connected thereto and 105 formed to engage the wall, a platform member seated on the tops of the bars, and engaged at the front side thereof with the stop shoulders, a transverse rod passed through two of the openings and engage- 110

able with the window frame, and bodily removable clamps arranged along the sides of the bars and having parts engaged with the top face of the platform member and parts 5 adjustably engageable with the under sides of the bars, the clamps being disposed between the inner side edge of the platform member and the window and acting to hold the platform member down onto the tops

of the bars and adjustably against the stop 10 shoulders.

In testimony whereof I have affixed my signature in the presence of two witnesses.

DAN NEWTON.
